UNITED STATES PATENT OFFICE.

MARGARET LARKIN, OF NEW YORK, N. Y.

BRASSIÈRE.

Application filed March 13, 1923. Serial No. 624,699.

To all whom it may concern:

Be it known that MARGARET LARKIN, a citizen of the United States of America, residing at New York, in the county of New York and State of New York, has invented certain new and useful Improvements in Brassières, of which the following is a specification.

This invention relates to garments and 10 more particularly to those types of garments known as brassières, camisoles and bust-confiners.

An object of the invention is to provide a garment which will snugly and properly 15 confine and support the wearer's busts and at the same time be capable of varied and easy adjustment to the body of the wearer.

The invention further provides a cool and light garment adapted to be worn by women 20 when engaged in athletic pursuits, evening-dress affairs or house work.

Further objects will be clearly understood from the following specification taken in conjunction with the accompanying drawing 25 ing wherein like numerals designate like parts.

Figure 1 is a front view of the garment positioned on the wearer's body;

Figure 2 is a similar view of the garment 30 detached from the wearer's body; and

Figure 3 is a rear view of the garment shown in Figure 2.

The numeral 1, designates the brassière having a front bust covering portion 2, 35 adapted to extend from one side of wearer's body to the other and from a point above the wearer's bust to a point substantially below thereof. The portion 2, is provided with side portions 3 and 4, a lower edge 5, 40 and an upper edge 6. Extending from the lower portion of said covering 2, at approximately the center thereof is an integral extension 7 having a loop 8, in which is positioned a fastener 9. The upper part of said 45 covering 2, at both sides of its center is provided with substantially long, elongated shoulder straps 10 and 11 which are preferably integral with the part 2, and of inelastic fabric.

50 The back of said garment is formed of a back covering and connecting part 12, composed of two similar sections 13 and 14 detachably connected to each other at 15, as by hooks and eyes or snap fasteners. Each 55 section comprises preferably two spaced

apart and vertically extending inelastic strips 16 and 17 connected together by a plurality of horizontally extending spaced apart elastic strips 18. The top of each strip 17 is provided with fastening means 60 19, such as buckles to which the shoulder straps 10 and 11 are adapted to be detachably and adjustably connected.

Horizontally extending toward the rear from each of the vertical sides 3 and 4 are a 65 plurality of spaced apart straps 20. It will be particularly noted that the upper straps 20, are in alignment with the upper part of the covering 2, the lower straps in alignment with the lower portion thereof, and 70 the middle straps in alignment with middle portion of the covering. The straps 20, may be formed as integral with the covering 2, or be separate straps connected to the side edges as by stitching and are preferably 75 elastic. As clearly shown in the drawing the free ends of the straps 20, are threaded thru the openings 21, formed by the straps 16, 17 and 18 and return bent upon themselves and fastened to themselves by 80 the well known slideable buckles 22. By this construction the straps 20 will be adjustable as to length tho the buckles when satisfactorily positioned by the wearer will remain in place by the well known binding 85 action.

If desired the strips 17, may be provided with flexible stiffening means such as celluloid, bone or metal. The elastic in the strips 18, allows the garment to automatically expand and contract in response to certain movements of the wearer's body when the garment is positioned thereon.

Having thus described my invention what I claim is:

A brassière comprising a front body covering portion and a rear body covering portion, said rear body covering portion consisting of a plurality of sections with each section comprising a plurality of spaced 100 apart vertically extending inelastic strips connected together by a plurality of spaced apart elastic strips, said front body covering portion and said rear body covering portion being connected to each other by a plurality 105 of adjustable straps positioned between said elastic strips and around said inelastic strips.

In testimony whereof I affix my signature.
MARGARET LARKIN.
